UNITED STATES PATENT OFFICE.

IRVING B. EPPENSTEIN, OF ELGIN, ILLINOIS, ASSIGNEE TO ILLINOIS WATCH CASE COMPANY, OF ELGIN, ILLINOIS, A CORPORATION OF ILLINOIS.

COMPACT CONTAINER.

Application filed January 8, 1923. Serial No. 611,460.

To all whom it may concern:

Be it known that I, IRVING B. EPPENSTEIN, a citizen of the United States, residing at Elgin, in the county of Kane and State of Illinois, have invented certain new and useful 5 Improvements in Compact Containers, of which the following is a specification.

This invention relates to a receptacle or container designed especially for holding 10 certain toilet accessories, as, for example, rouge and powder compacts; more particularly it is concerned with the construction of such a container which renders it suitable for convenient carrying and use, and for easy renewals as required.

According to the present invention a container is provided in the form of a case having two covers and an intermediate partition all hinged to swing about a common axis; in 20 one cover may be contained a powder compact together with puff therefor; in the partition may be provided a mirror by which the usefulness of the device is enhanced; and in the other cover provision is made for releasably holding a rouge compact together with 25 puff therefor. My invention is concerned not only with a case so constructed and arranged, but also with certain means by which one or both of the compacts are releasably 30 secured in place so as to permit of a ready substitution of refills, whenever desired.

An exemplification of this invention is set forth in the accompanying drawing in the manner following:

Figure 1 is a plan view of the container, the covers being opened out so as to expose the contents to view;

Fig. 2 is a transverse section on line 2—2 of Fig. 1; and

Fig. 3 is an enlarged fragmentary view showing the means for releasably holding the rouge compact.

The present container makes use of two covers A and B between which is a partition 45 ring C, all having a common hinged connection at 5. The covers A and B are formed with inwardly facing marginal walls or flanges 6 and 7, respectively, so as to provide between them an enclosure of ample size for 50 the reception of the intended contents. Within the ring C is supported a partition element 8 preferably in the form of a mirror which, if desired, may also be double-faced so as always to present a reflecting surface 55 regardless of its position between the two

covers. As shown, the ring is formed to lie within the container in such a manner as not to interfere in any way with closing of the covers. Any suitable lock 9 may be provided for normally holding the covers together.

Within the cover A may be arranged a powder compact D with which is associated a removable puff 11 of lamb's wool or any other desirable material. With the mirror ring closed down upon this compact, as illustrated in Fig. 2, the compact is thoroughly protected even though the parts in the other cover B be exposed. The powder compact may be secured in place in any desired manner. In the cover B is provided a circular 70 plate 12 adapted to be secured frictionally or otherwise within the flanged walls 7 thereof, this plate having a central cup with depending circular walls 13 and a bottom 14, all as best shown in Fig. 2. The cup thus formed 75 is adapted to receive a rouge compact E the size of which is smaller than the powder compact, but ample nevertheless in proportion thereto. To hold in place such a rouge compact, I have shown a lip 15 struck inwardly from the cup walls and adapted to overlie the compact at one point, and substantially opposite thereto a second overlying lip 16 which is carried by a spring arm 17 that may be fastened to the wall 13 as by 80 means of a rivet 18. The spring means thus provided for completing the lock for such a compact is arranged beneath the plate 12 and hence is concealed from view. To facilitate its operation a finger piece 19 is projected 85 upwardly from the spring arm being extended through a slot 20 in the plate so as to occupy a position which is convenient for the finger. Over the rouge compact may be arranged a second puff 21 of lamb's wool or any 90 other suitable material.

A container of the kind described may be produced at no great expense and with the contents arranged as described will be found very convenient for use. As the powder and rouge compacts are secured in separate compartments between which lies the swinging mirror, there is no possibility of the one making direct contact with the other, although both are exposed simultaneously if the mirror be swung to an intermediate position. In addition it should be noted that each compact is independently renewable so that, if one is consumed faster than the other, it is unnecessary to obtain a combination com- 110

pact in order to prolong the serviceability of the device.

I claim:

- 5 1. A container in the form of a case having a pair of hinged covers formed with marginal walls, a plate extending transversely between the marginal walls of one cover and formed with a depending cup adapted to receive a compact, there being an opening through the peripheral walls of the cup, and spring means secured to the exterior of the peripheral cup walls adapted normally to project in part through the opening to engage a compact within the cup whereby the compact is releasably held in place.
- 10 2. A container in the form of a case having

a pair of hinged covers formed with marginal walls, a partition swingingly arranged between the two covers, a compact secured within one cover and formed of a size adapted to occupy substantially the entire space therewithin, a second compact of smaller size adapted to occupy only a portion of the space within the other cover, a spring lock for holding the second compact in place, and means for securing the lock to the cover adapted also to conceal the lock from view, substantially as described.

IRVING B. EPPENSTEIN.
